UNITED STATES PATENT OFFICE.

HENRY F. FULLER, OF CHICAGO, ILLINOIS, ASSIGNOR TO THE WALMSLEY,
FULLER & COMPANY, OF SAME PLACE.

ACETYLENE-GAS GENERATOR.

SPECIFICATION forming part of Letters Patent No. 560,405, dated May 19, 1896.

Application filed December 17, 1895. Serial No. 572,396. (No model.)

To all whom it may concern:

Be it known that I, HENRY F. FULLER, a citizen of the United States, residing at Chicago, in the county of Cook and State of Illinois, have invented a new and useful Improvement in Gas-Generators, of which the following is a specification.

My invention relates to that class of generators in which the gas is produced by causing materials which have a chemical affinity to contact and by such contact effect the desired chemical combination; and while my invention may be employed in the manufacture of gases of various kinds and for various purposes it is intended more especially as a generator for use in the production of acetylene gas by causing calcium carbide in the solid state to contact with water.

My object is to provide a generator of a construction adapting it for the production more especially of acetylene gas, and which will operate automatically to supply the gas as fast as but no faster than required and at an approximate predetermined pressure.

A generator constructed in accordance with my invention may be employed as a supplying means for a number of gas-burners, or may be of a size rendering it readily portable and provided with a burner to operate as a hand-lamp, as illustrated in the accompanying drawing, which shows a vertical central section of such a construction.

A is a preferably cylindrical vessel or lamp-body open at the top, provided with a base *t* and having a handle *t'*. Fitting into the top of the vessel A is a structure comprising a top plate *s*, annular receptacle or chamber *r*, and central downward-extending part *q*, all in rigid relation. The part *q* consists of a cylindrical neck *q'*, which forms the inner annular wall of the chamber *r* and is fastened to the top plate *s* around a central preferably threaded opening *s'* in the latter. Below the chamber *r* the neck portion *q'* is expanded and forms the shell or annular wall *q''* of a chamber *q'''*, which wall extends nearly to the base *t* and at its lower end portion is close to but out of contact with the wall of the vessel A.

The construction of the part *q* is such that between its lower end portion and the wall of the vessel A is a narrow annular chan-

nel *p* and above the said channel a chamber *p'*, which grows larger more or less gradually to the base of the chamber *r*. On the part *q* toward the lower end thereof is an annular 55 inward-extending plate *n*, carrying at its inner circumference a vertical guide-sleeve or guide-cylinder *n'*, which with the plate *n* forms an annular receptacle *m* above the plate *n* and an annular space or inverted receptacle *m'* below the said plate. Fitting and sliding vertically in the guide-cylinder *n'* is a cup or receptacle *l*, having a cylindrical wall *l'* of thin sheet material and a base *l''*, either perforated or formed of mesh-wire to afford a 60 sieve. The cup *l* is fastened upon and supported by a rod *k*, which extends downward therefrom around the base of the part *q* and thence upward through a tube *r'*, which passes through the chamber *r* and through an opening *s''* in the top *s*. The upper end portion of the rod *k* is provided with teeth forming a rack *k'*, engaging the top plate at one edge of the opening *s''* and held normally in such engagement by a finger-spring *s''*. Pressure of 65 the rod at its upper end portion against the resistance of the spring *s''* will free the rack from engagement with the top plate and permit it to be raised and lowered to raise and lower the cup *l* in the guide-cylinder *n'*. 70

Extending vertically through the chamber *r* is a tube *r''*, provided toward its lower end portion with openings *r'''* into the said chamber. In the tube *r''* is a piston-plug *r'''*. The top portion of the tube *r''*, which extends 75 above the plate *s*, is cut away to form a cam *r''''*, and on the plug *r''''* is a pin *r'''''*, which rests upon the cam-surface *r''''* and supports the plug. Turning of the plug *r''''* will cause its pin *r'''''* to descend upon the cam, whereby the 80 lower end portion of the plug will descend across the openings *r'''* and close the latter. Turning of the plug in the opposite direction will cause it to rise upon the cam-surface and clear the openings *r'''*. When the device is to 85 be employed as a lamp, as shown, a tube *i*, having a valve *i'*, may be secured at its lower end in the opening *s'* and provided at its upper end with a burner *i''*.

The entire structure, consisting of the top 90 plate *s*, annular chamber *r*, and part *q*, may be lifted out of the vessel A, and the outer an-

nular surface of the chamber r fits closely against the wall of the vessel A , the whole structure being supported by the top plate.

In operation the said structure is lifted out of the vessel A and the rod k pushed downward to free the receptacle l from the guide-cylinder n' . The said receptacle is filled with calcium carbide, preferably in lumpy or granular form, and the cup then adjusted in the guide-cylinder and raised according to a scale x on the rod k until the sieve l^2 is at a desired height above the lower end of the guide-cylinder. The structure is then placed in the vessel, the plug r^4 removed, and the vessel filled to, say, the level x' with water. As the water rises to the sieve l^2 it contacts with the calcium carbide in the vessel l , causing the rapid production of acetylene gas, which rises into the chamber q^3 , fills the latter, and then by exerting its pressure in a downward direction through the sieve against the water forces the latter downward against the resistance of the pressure of the water column in the chamber p' , thus practically stopping further generation of the gas and holding the same under the pressure of the said water column. On opening the cock i' gas, under the pressure stated, will escape and may be ignited at the burner i^2 . As the gas escapes and pressure in the chamber q^3 is reduced the water will again rise to the sieve, more gas will be generated, and the operation described repeated. The lower end portion of the shell q^2 should extend so far down as to be always sufficiently below the sieve l^2 in the adjustment of the latter to prevent gas from escaping to the chamber p' and vent-opening s^2 . For a short distance below the plate n the guide-cylinder n' is a solid ring, and the lower end portion of the cylinder is provided with one or more recesses n^2 . In the plate n at one point is an opening n^3 , from which a tube n^4 may extend downward to the plane of the upper ends of the notches or recesses n^2 . The space m' between the lower end of the tube n^4 and plate n may thus operate as a gasometer or equalizer, which is very useful in a device of this nature. The annular receptacle m about the cup l may be initially provided with a small amount of calcium carbide, which will operate as an absorbent and tend to abstract from the gas in the chamber q^3 any moisture carried thereby. In the event that water should at any time accumulate in the annular vessel m it will drain through the opening n^3 and tube n^4 . If in operation the calcium carbide, becoming spongy, should swell beyond the capacity of the vessel l , the surplus material will drop therefrom into the annular vessel m , and, through absorption of moisture from the chamber q^3 or rise of water through the tube n^4 , also gradually generate acetylene gas.

Assuming that the water column in the chamber p' extends to the line x' , when the water contacts with the carbide on the sieve l^2 , a certain pressure will be exerted against

the gas generated, which pressure will increase gradually as increased generation of gas raises the water column, and the degree of compression of the gas in the chamber q^3 may be increased by lowering the vessel l in the guide-cylinder n' and diminished by raising the vessel. If no means are provided for maintaining a uniform water column in the chamber p' , and the water-line in the vessel A is lowered by use of the water in the generation of gas, the gas-pressure may be increased from time to time in the chamber q^3 by pushing down the rod k to lower the vessel l .

When the sieve l^2 is in a plane above the recesses n^2 , the pressure of the gas in the chamber q^3 will be normally exerted against an area bounded by the guide-cylinder wall n' , and the rise and fall of the water in said area under variations of gas-pressure will produce but little variation in the water-line x' , and therefore little change in the pressure of the water column. When the gas generates so rapidly as to force the water below the tops of the recesses n^2 , the gas will exert itself against a much larger area of water and raise the water column more rapidly, causing a rapid increase of water-pressure. This all tends to maintain a uniform standard of gas-pressure in the chamber q^3 and to prevent the too ready generation of gas.

In the event that through splashing of the water against the sieve in carrying the lamp about, or from any other cause, gas should be generated much more rapidly than is desired the pressure of the gas from the chamber q^3 against the water below the sieve will cause the whole structure to rise in the vessel A , and thus operate as an effective safeguard against explosion.

As a means for maintaining the water-level at x' the chamber r may be filled with water and the plug r^4 raised to the position shown in the figure, whereby as fast as water is consumed in the formation of gas it will be supplied through the openings r^3 .

While I have shown and described my improvements in connection with an acetylene-lamp, it may be of a much larger size than would be practicable to render it portable, and a pipe leading to any number of burners may be connected to the opening s' . My improvements may also be found desirable for use in generating gas other than acetylene. While I have shown and described my improvements as I prefer to provide them, they may be modified in the matter of details without departing from the spirit of my invention as defined by the claim.

What I claim as new, and desire to secure by Letters Patent, is—

In a generator for the production of gas from two bodies of chemically-coacting materials, one of which is solid and the other liquid, a vessel for the liquid, a shell supported in said vessel and containing a gas-chamber having an outlet at its upper end

portion and opening at its lower end into the vessel, a circumferential inward-extending plate in the shell above the lower end thereof, a guide-sleeve secured to and extending 5 below the said plate to a plane above the lower end of the shell and forming with the shell a gas-space about the said sleeve, and a receptacle for the solid material having a perforate lower portion and supported in said 10 guide-sleeve, a space between the shell and side wall of the vessel forming a chamber for a liquid column, whereby the gas generated

by the contact of the materials passes through the solid material as generated and fills the chamber and exerts downward pressure, 15 through the body of solid material, against the liquid to separate the said materials against the resistance of the liquid column and check the generation of gas, substantially as and for the purpose set forth.

HENRY F. FULLER.
